UNITED STATES PATENT OFFICE.

JOHN GRAVES, OF BROOKLYN, NEW YORK.

MANTEL.

SPECIFICATION forming part of Letters Patent No. 350,928, dated October 19, 1886.

Application filed January 25, 1886. Serial No. 189,577. (No model.)

To all whom it may concern:

Be it known that I, JOHN GRAVES, of Brooklyn, in the county of Kings and State of New York, have invented an Improvement in Mantels, of which the following is a specification.

Cast-iron has been employed for mantels and fire-places, and in some instances sheet metal has been employed, especially with gas-burning fire-places.

10 My present invention is made with reference to the use of sheet-metal mantels in imitation of marble or wood mantels and at a much less cost, and possessing greater durability, because they are not liable to crack or become injured in use or detached from the wall.

In the drawings, Figure 1 is an elevation of a mantel. Fig. 2 is a horizontal section at the line *x x*, and Fig. 3 is a sectional view at 20 the line *y y*.

The ornamentation of the mantel and its general shape and configuration do not form a necessary part of this invention, as the form and design will be varied to suit the taste; 25 but the sheet metal is to be pressed up in dies by suitable power—such, for instance, as a hydraulic press—and panels, ribs, and beads or other ornaments are to be pressed into or upon the sheet metal, with the twofold purpose of ornamenting the surface and of stiffening the same, so as to cause the sheet metal to retain the form that may be given to it by the dies. The pilaster portion *a* of the mantel is stiffened by the metal being bent back-

35 wardly to form the profile portion *b*, and the wall-plates *c* are bent with return-flanges, that allow for fastening the wall-plates to the chimney. The wall-plates, the profile portions, and the pilasters at each side are all 40 struck up out of one piece of sheet metal, so as to avoid joints and render the parts very strong and stiff. The inner border or jambs, *d*, are adapted to filling the space between the pilasters *a* and the fire-place *f*, and these 45 jambs are preferably made in one with the pilaster portion *a*, and the returned flanges *e* allow for the jambs being firmly built in with mason-work or plaster. In the vertical portions of the jambs bars *g* are introduced, having lugs *i*, that project through holes in the sheet metal of the jambs, and upon which the grate or summer-piece can be hooked. The

55 pilasters extend upward and are made in one with the frieze or arch *h*, and in the middle of the frieze the sheet metal on one side will be set into the sheet metal on the other side and be bolted or riveted together, as seen in Fig. 3; or the metal may be united by double-seamed bends. This construction allows the frieze to be spread more or less to suit the 60 width of mantel, and the ornamental centerpiece *k* is bolted on to cover the joint. There is a top flange, *t*, upon the frieze, bent backwardly to stiffen the metal and form a rest for the shelf. The shelf *l* is made with a bent-up or rolled front edge to stiffen the same, and the back edge is bent either upwardly or downwardly to form a stiffening-flange that is connected to the chimney-breast. When 65 turned down, it passes behind the upper parts 70 of the wall-plates *c c*.

The summer-piece *m* is made of sheet metal with ornamental ribs and coves in it and with openings in the same for the purposes of ventilation, as usual in summer-pieces; but 75 where the fire-place is to be closed or to receive a stove-pipe the movable plate *m* will be made with the flanges as aforesaid, but without openings except such as are required for the stove-pipe. 80

The angles of the pilasters, especially the outer angles between the profile portions and the pilasters, are liable to concussions from coal-scuttles and other articles. To stiffen and strengthen the same the edges are rounded and 85 corrugated, as shown at *b'*.

I claim as my invention—

1. The sheet-metal mantel having the profile piece, pilaster, and wall-plates at each side in one piece of sheet metal stamped up 90 to a shape in dies, and having stiffening ribs or coves, substantially as set forth.

2. The sheet-metal mantel having panels, ribs, or coves pressed into the same, and the two halves setting into each other at the center of the frieze and attached together, and having an ornament over the joint at such central portion, as set forth. 95

3. The mantel-front having at each side a pilaster, *a*, and a profile piece, *b*, in one piece 100 of sheet metal, with corrugations *b'* at the edges, substantially as set forth.

4. The sheet-metal mantel-front having the pilaster and frieze portions in one and pressed

up with stiffening ribs and coves, substantially as set forth.

5. The sheet-metal mantel-front having pilasters and frieze and a backwardly-bent flange at the top edge, in combination with the sheet-metal mantel-shelf, substantially as set forth.

6. The sheet-metal mantel-front having pilaster and frieze and jamb in one piece at each side of the fire-place, substantially as set forth.

7. The sheet-metal mantel-shelf having a 10 downwardly-rolled edge at the front and a flange at the back, substantially as set forth.

Signed by me this 19th day of January, A. D. 1886.

JOHN GRAVES.
